COMBINED CURTAIN ROD AND HOLDERS THEREFOR

George G. Jetter, Fort Recovery, Ohio, assignor to Fort Recovery Industries, Inc., Fort Recovery, Ohio

Filed Dec. 9, 1971, Ser. No. 206,596

Term of patent 14 years

Int. Cl. D8—08

U.S. Cl. D8—209

FIG. 1 is a side elevational view of a combined curtain rod and holders therefor showing my new design, the rod portion shown broken away to illustrate indeterminate length;

FIG. 2 is a cross sectional view taken on line 2—2 of FIG. 1;

FIG. 3 is a cross sectional view taken on line 3—3 of FIG. 1;

FIG. 4 is a cross sectional view taken on line 4—4 of FIG. 1;

FIG. 5 is a cross sectional view taken on line 5—5 of FIG. 1;

FIG. 6 is an end elevational view of both ends of the holder taken on lines 6—6 of FIG. 1.

I claim:

The ornamental design for a combined curtain rod and holders therefor, substantially as shown and described.
